UNITED STATES PATENT OFFICE.

HENRIE D. STONE, OF BOSTON, MASSACHUSETTS, ASSIGNOR TO THE ADAMS MANUFACTURING COMPANY, OF PORTLAND, MAINE.

HEELING-MACHINE.

SPECIFICATION forming part of Letters Patent No. 315,675, dated April 14, 1885.

Application filed October 6, 1884. (No model.)

To all whom it may concern:

Be it known that I, HENRIE D. STONE, of Boston, county of Suffolk, State of Massachusetts, have invented an Improvement in Heeling-Machines, of which the following description, in connection with the accompanying drawings, is a specification, like letters on the drawings representing like parts.

This invention relates to and is an improvement upon the machine described in an application, Serial No. 125,152, filed March 22, 1884.

In this present invention I have arranged the parts so as to compress the heel after pricking it and also after driving the staples through it, the awls and staples entering the heel better when the latter is not in compressed condition.

The particular features in which my invention consists will be pointed out in the claims at the end of this specification.

Figure 1 is a side elevation of a heeling-machine embodying my invention, the dotted lines showing the arm and its connected parts turned outward to receive upon or to permit a boot or shoe to be taken from it. Fig. 2 is a front elevation of Fig. 1; Fig. 3, a sectional detail of the upper end of the machine to show the driver-plate in its upper position or after the drivers have driven the staples into the sole and heel. Fig. 4 is a top view of the supporting-plate shown in Figs. 1 and 2. Fig. 5 is a section of Fig. 4 in dotted line x - x . Fig. 6 is a detail in partial elevation and section to show the staple-guides, staple-drivers, driver-plate, and the supporting-plate and some of their attached parts. Fig. 7 is a section of Fig. 5 in the line x' - x' , looking down upon the driver-plate. Fig. 8 represents the parts which are substituted for some of those shown in Figs. 4, 5, and 6, when the sole and heel are to be pricked for the reception of the staples; and Fig. 9 is a top view of the supporting-plate on which the sole rests when it and the heel are being pricked.

The plate D^4 , its conical pointed tubes 4, spurs 5, awls d , plate 24, studs 23, plate g , stud g' , spring g^2 , corrugators g^3 , pivoted at 15, sleeve g^4 , screw g^5 , staple-guides 19, and staples s are all substantially as in the said application, where they are designated by like letters. The frame A has suitable bearings to

sustain the driving-shaft A', which is provided with a belt-pulley, A², and a balance-wheel, A³. The main shaft A' has a pinion, A⁴, which engages the toothed wheel B loose on the shaft B', and provided at its end with the crank B', said shaft B' having fast upon it a clutch, B², of ordinary construction, preferably such as described in United States Patent No. 169,394, 60 which is provided with mechanism whereby the shaft B' is stopped after each complete revolution, the stopping-point of the shaft being with the crank-pin B² in its lowest position. The crank-pin B² receives the strap of 65 a connecting-rod, B⁴, which is joined by a pin, a, with the carriage C, having, preferably, dovetailed edges, and fitted into guideways C' C', forming part of the frame-work. The upper end of the carriage C is provided with 70 a box, which receives through it, and also through the lower end of the arm E, a bolt, a', by which the carriage and arm are so connected that the arm may be turned into the dotted-line position, Fig. 1, to remove or apply the boot or shoe to which the heel is to be attached. The arm E is provided with a locking device, shown as a balanced dog, a³, having a lug, a⁴, (shown in dotted lines, Fig. 1,) which, when the said lug is as in full lines in 80 said figure, keeps the arm E in vertical position. The arm E at its upper end is bored or countersunk for the reception, as shown in dotted lines, Fig. 2, of the tubular shank of the driver-plate b, (shown separately in Figs. 5, 6, and 7,) 85 the said plate being provided with projections b', to receive and, in connection with pins b², to hold the drivers b³, which in this invention are made of flat steel bars having a width and thickness substantially equal to the crowns of 90 the staples s, to be driven thereby. The arm E has a central bearing, c, and a second bearing at its upper end to receive a rod, D, which at its upper end has connected with it the heel-supporting plate 24, provided with a series of elongated holes, 22, through which the staples s are driven into the sole and heel. From the lower end of this plate depend the staple-guides 19, consisting, essentially, of 100 narrow bars of metal grooved at their contiguous edges to receive the legs of the staple s, as best shown in Fig. 1, the said staple-guides at their lower free ends entering suitable holes in the driver-plate. The rod D, near its cen-

tral part, is provided with an adjustable collar, *e*, below the said collar and between it and the bearing *c* is a spiral spring, *e'*, which latter surrounds the said rod. The supporting-plate 5 24 at its upper side is provided with the register-pins 23, which enter the register-holes previously made in the inner sole by the conical projections 5 of the supporting-plate *D*⁴, (see Fig. 8,) upon which the sole rests when it and 10 the heel are being pricked by the awls *d*. At its outer edge the supporting-plate is provided with a shield, *H*, which is extended downward to cover the staple-guides and the upper end of the arm *E*.

15 The normal condition of the parts previous to inserting the staples *s* through the inner sole into the heel is as in Figs. 1 and 2, in which it will be noticed, especially in Fig. 1, that the driver-plate *b* is some distance below 20 the supporting-plate 24. A boot or shoe with its heel temporarily connected thereto by one or more nails, and with the sole and heel pricked, is placed upon the supporting-plate with the parts in the condition represented in 25 Figs. 1 and 2, and the shaft *B'* is started. Movement of the shaft elevates the carriage *C*, and with it the driver-plate *b* and supporting-plate 30 24, the latter being lifted by the action of the spiral spring *e'*. As soon as the supporting-plate 24 has been lifted sufficiently to merely pinch the sole and its attached heel between it and the plate *g*, the supporting-plate 35 24 comes to rest or stops, and the spring is compressed as the arm *E* continues to rise, and during such movement of the arm *E*, after the supporting-plate has been arrested, the drivers *b*³ act against the crowns of the staples *s*, forcing them upward through their guides and 40 through the holes 22 in the supporting-plate and into the sole and outward into the heel. As the crowns of the staples are brought snugly against the inner sole, the crank-pin *B'* arrives nearly in its highest position, and thereafter as the crank-pin passes to its highest position, the staples having been driven, the 45 heel is compressed and solidified, and the "settle" thus given to the stock is held by the corrugated legs of the staples. The outer portion or periphery of the heel will be corrugated, substantially as in the application referred to, during the time that the heel is being compressed.

To enable the machine just described to 55 prick the soles and heels preparatory to driving staples therein, the arm *E* will be removed, and another arm just like it will be connected with the carriage *C* by the same bolt, *a'*. This arm so substituted for arm *E* will have secured to its upper end the metal plate *d*², Fig. 60 8, shaped like the driver-plate *b*, but which is provided with a series of awls, *d*. The rod *D*, when pricking is to be done, has attached to its upper end a supporting-plate, *D*⁴, having conical-pointed tubes 4 and pins or studs 65 5, which in function and operation are substantially the same as parts designated by like letters in the said application. In this

invention I have, however, added to the plate *D*⁴ a nail-receiving tube, 6, and I have added to the plate *d*² a driver, marked 7, which, in 70 operation, drives a nail, 8, into the sole, and through it into the heel as the awl-plate *d*² is lifted to drive the awls *d* through the sole and heel, the said nail temporarily securing the sole and heel together, as stated. The framework has attached to it a projection or lug, *m*, against which the lower end of the rod strikes as the carriage and arm *E* are drawn down, the said projection acting to stop the rod while the arm is descending, thus insuring the placing of the supporting-plate above the driver-plate. 75

I claim—

1. In a heel-ing-machine, the plate *g*, against which the outer end of the heel is pressed, the 85 reciprocating carriage, the arm *E*, connected therewith, and the driver-plate provided with the drivers *b*³, combined with the rod *D* and its connected supporting-plate provided with the guides 19, to operate all substantially as 90 described.

2. In a heel-ing-machine, the plate *g*, against which the outer end of the heel is pressed, the carriage *c*, and the arm *E*, connected with the said carriage, and the driver-plate and drivers, and the rod *D*, provided at its upper end with the supporting-plate and extended into guides in the said arm, and the spring surrounding the said rod and normally keeping the supporting-plate elevated above the driver-plate, combined with means, substantially as described, to actuate the said parts, whereby by the sole and heel of the boot and shoe are first held between the plate *g* and the supporting-plate, upward movement of the arm *E* 105 after the sole and heel are held in place between the said plates effecting the elevation of the driver-plate to drive the fastenings, further upward movement of the arm after driving the fastenings and securing the heel 110 to the boots and shoes consolidating or compacting the heel, as set forth.

3. In a heel-ing-machine, the carriage and its arm provided at top with awls, and the rod *D* and supporting-plate and spring *e'*, 115 and the plate *g*, combined with means to move the carriage, the heel to be pricked being first caught between the supporting-plate and the plate *g* when the supporting-plate and rod remain at rest, while the arm *E* and carriage 120 continue to rise to enable the awls to penetrate the work, substantially as described.

4. In a heel-ing-machine, the supporting-plate provided with the conical pointed tubes 4 and open-ended nail-tube 5, combined with 125 the rod, its plate *d*², a series of awls, and a driver, 7, and with means, substantially as described, to operate the said rod and plate.

5. In a heel-ing-machine, the carriage and the arm *E*, pivoted thereon, combined with 130 the locking device to hold the arm in upright position, all operating substantially as described.

6. The carriage, the arm *E*, its plate, and

the rod D, the plate attached to its upper end, and the spiral spring surrounding the shaft, combined with a projection to arrest the said rod as the arm E is lowered, substantially as described.

5 7. The arm E and its attached staple-drivers combined with the spring-supported rod held in bearings in the said arm, and provided with a supporting-plate having staple-
10 guides, the said parts being constructed and

combined to operate substantially as described.

In testimony whereof I have signed my name to this specification in the presence of two subscribing witnesses.

HENRIE D. STONE.
